[57] CLAIM

The ornamental design for a broom cap, as shown and described.

DESCRIPTION

FIG. 1 is a perspective view of a broom cap showing my new design, the broken lines showing of a handle and broom fibers being for illustrative purposes only and forming no part of the claimed design;

FIG. 2 is an enlarged perspective view thereof;

FIG. 3 is a side elevational view as seen from the left of FIG. 2;

FIG. 4 is an elevational view of the opposite side thereof;

FIG. 5 is a top plan view thereof;

FIG. 6 is a front elevational view thereof, the rear being a mirror image; and,

FIG. 7 is a bottom plan view thereof.
